ATTORNEY

UNITED STATES PATENT OFFICE.

JOSEPH ROTH, OF NEW YORK, N. Y., ASSIGNOR OF FIFTY PER CENT TO HAROLD I. WILLIAMS, OF NEW YORK, N. Y.

DRILL ATTACHMENT.

Application filed April 16, 1927. Serial No. 184,349.

This invention relates to improvements in drill attachments, and more particularly to an article of equipment for portable power drills such as electric drills.

5 It is well known that the ordinary type of electric drill is not suitable for cutting materials such as stone, concrete, brick and plaster, and as a consequence it is frequently necessary when such substances are encountered, for a mechanic to resort to the time consuming and laborious practice of hand drilling, that is repeatedly striking a star drill, cold chisel or the like with a heavy instrument such as a hammer. A twist drill 10 for such purpose is wholly useless and the result is that the usual portable power drill must remain idle while much time and labor is expended.

The object of the present invention is to 20 eliminate such laborious and time consuming practices by rendering the power drill capable of producing a reciprocative longitudinal as well as a rotary motion, so that by utilizing the proper drill, the hand process 25 may be wholly eliminated and the drilling accomplished with dispatch and at a minimum expenditure of labor.

A feature of the present invention is its 30 adaptability to application to portable power drills without necessitating their alteration in any manner whatsoever.

Another feature of the invention is the supporting of the drill bit in such a manner that while receiving the force of the hammer blow it is at all times under the guidance and control of the user, thus enabling it to be rotated or reciprocated during the drilling operation.

With the above and other objects in view, 40 one embodiment of the invention consists in the novel construction, combination and arrangement of parts which will be fully set forth in the following specification and illustrated in the accompanying drawing, in which:

Figure 1, is a side view of a power drill, equipped with a vibratory drill attachment constructed in accordance with this invention,

50 Figure 2, is an enlarged longitudinal sectional view through the drill attachment,

Figure 3, is a sectional view taken on line 3—3 of Figure 2, and

55 Figure 4, is a sectional view taken on line 4—4 of Figure 2.

Referring to the drawings in detail, a portable electric drill 10 is equipped with the customary tool holder 11 in which the various instruments are operatively supported in the customary manner.

60 The drill attachment 12 comprises a tubular body 13 equipped with end closures 14 which are formed with openings 15 disposed in axial alignment with the longitudinal axis of the body 13. These openings form bearings for the drill operating members to be more fully hereinafter described.

65 Rotatably mounted in one of the openings 15 is a shaft 16 carrying at its inner end a head 17 projecting beyond the end of the body 13 for entrance into the tool holder 11 of the portable drill. The inner end of the head 17 is formed with an axial recess 18 and cam faces 19 forming diametrically opposed shoulders for a purpose to be more 70 fully hereinafter described.

75 Slidably mounted in the opening 15, opposite that in which the shaft 16 is mounted, is a shank 20 which projects beyond the end of the body 13 and carries a tool holder such as the chuck 21. Like the shaft 16, the shank 20 is provided with a head 22 at its inner end having cam faces 23 forming shoulders at diametrically opposed points. These cam faces and shoulders cooperate with those on 80 the head 17 in converting the rotary motion of shaft 16 into reciprocative motion in the shank 20. As shown the shank 20 projects beyond the inner end of the head 22 and into the recess 18 so that the parts will be 85 maintained in axial alignment. The shank 20 is formed with a flat surface 24 cooperating with the flattened face 25 of the opening 15 through which the shank projects to hold the shank and body against relative turning movement. The shoulder 26 formed on the shank at the outer end of the flat face 25 provides a stop to limit the longitudinal shifting movement of the shank relatively to 90 the body.

95 In order to hold the heads in cooperative relation, compression coil springs 27 are interposed between the heads 17 and 22 and their respective end closures 14 and thus 100 yielding maintain abutting ends of said heads in close contact.

105 In operation the device is placed in a drill as illustrated in Figure 1 with a drilling tool such as the star drill 28 gripped in the chuck 21. The body 13 is gripped in one hand to 110

guide and hold the drill steady. Upon imparting rotary motion to the shaft 16, the head 17 will be rotated and the cam faces 19 moving over the cam faces 23, will cause the shank to move longitudinally of the device and thus produce a series of blows on the end of the drill. By proper manipulation of the body 13 it will be obvious that the drill 28 may be caused to wear away the concrete plaster or similar substance, with great rapidity and the drilling of such substances may be easily and cheaply accomplished.

While in the foregoing there has been shown and described one embodiment of this invention, it is to be understood that minor changes may be made in the details of construction, combination and arrangement of parts without departing from the spirit and scope of the invention as claimed.

Having thus described my invention, what I claim as new and desire to secure by Letters Patent, is:-

1. A device for transforming rotary motion into reciprocating motion, consisting of a cylindrical casing, closures at the ends of said casing having axial openings, a driving shaft extending through one of the openings into the casing, a driven shaft ex-

tending through the opposite end opening into the casing, heads fixed respectively on the inner ends of both of said shafts, means to prevent rotation of said driven shaft relative to the casing, cam faces on each of said heads adapted to cause intermittent separation of said shafts, and means disposed between said heads and casing closures to retain said cam faces in normal engagement.

2. A device for transforming rotary motion into reciprocating motion, consisting of a cylindrical casing, removable closures at the ends of said casing, said closures having axial openings, a driving shaft extending through one of the openings into the casing, a driven shaft extending through the opposite end opening into the casing, hollow heads fixed respectively on the inner ends of both of said shafts, means to prevent rotation of said driven shaft relative to the casing, cam faces on each of said heads adapted to cause intermittent separation of said shafts, and resilient means disposed between said heads and casing closures to retain said cam faces in normal engagement.

In testimony whereof I affix my signature.

JOSEPH ROTH.
